(57) **CLAIM**

The ornamental design for a clip mechanism, as shown and described herein.

DESCRIPTION

FIG. 1 is a top perspective view of a clip mechanism according to one embodiment of the present invention.

FIG. 2 is a front view of a clip mechanism according to the embodiment of the present invention shown in FIG. 1.

FIG. 3 is a rear view of a clip mechanism according to the embodiment of the present invention shown in FIG. 1.

FIG. 4 is a right side elevation view of a clip mechanism according to the embodiment of the present invention shown in FIG. 1.

FIG. 5 is a top view of a clip mechanism according to the embodiment of the present invention shown in FIG. 1.

FIG. 6 is a bottom view of a clip mechanism according to the embodiment of the present invention shown in FIG. 1.

FIG. 7 is a top perspective view of a clip mechanism according to another embodiment of the present invention.

FIG. 8 is a front view of a clip mechanism according to the embodiment of the present invention shown in FIG. 7.

FIG. 9 is a rear view of a clip mechanism according to the embodiment of the present invention shown in FIG. 7.

FIG. 10 is a right side elevation view of a clip mechanism according to the embodiment of the present invention shown in FIG. 7.

FIG. 11 is a top view of a clip mechanism according to the embodiment of the present invention shown in FIG. 7.

FIG. 12 is a bottom view of a clip mechanism according to the embodiment of the present invention shown in FIG. 7.

FIG. 13 is a top perspective view of a clip mechanism according to another embodiment of the present invention.

FIG. 14 is a front view of a clip mechanism according to the embodiment of the present invention shown in FIG. 13.

FIG. 15 is a rear view of a clip mechanism according to the embodiment of the present invention shown in FIG. 13.

FIG. 16 is a right side elevation view of a clip mechanism according to the embodiment of the present invention shown in FIG. 13.

FIG. 17 is a top view of a clip mechanism according to the embodiment of the present invention shown in FIG. 13.

(Continued)

FIG. 18 is a bottom view of a clip mechanism according to the embodiment of the present invention shown in FIG. 13. FIG. 19 is a top perspective view of a clip mechanism according to another embodiment of the present invention. FIG. 20 is a front view of a clip mechanism according to the embodiment of the present invention shown in FIG. 19. FIG. 21 is a rear view of a clip mechanism according to the embodiment of the present invention shown in FIG. 19. FIG. 22 is a right side elevation view of a clip mechanism according to the embodiment of the present invention shown in FIG. 19. FIG. 23 is a top view of a clip mechanism according to the embodiment of the present invention shown in FIG. 19; and, FIG. 24 is a bottom view of a clip mechanism according to the embodiment of the present invention shown in FIG. 19. Elements of the mechanisms in the attached figures are in broken and/or phantom lines for illustrative and/or environmental purposes only and form no part of the claimed design.
